UNITED STATES PATENT OFFICE.

MARTIN P. VAN RYZIN AND HERMAN G. SAECKER, OF APPLETON,
WISCONSIN.

KNIFE-SPACER FOR PAPER-STOCK ENGINES.

SPECIFICATION forming part of Letters Patent No. 728,763, dated March 24, 1903.

Application filed January 22, 1903. Serial No. 140,059. (No model.)

To all whom it may concern:

Be it known that we, MARTIN P. VAN RYZIN and HERMAN G. SAECKER, citizens of the United States, and residents of Appleton, in 5 the county of Outagamie and State of Wisconsin, have invented certain new and useful Improvements in Knife-Spacers for Paper-Stock Engines; and we do hereby declare that the following is a full, clear, and exact de- 10 scription thereof.

Heretofore it has been common to employ built-up wood spacers between the knives of shells of paper-stock engines, the veneer ply or plies of each spacer being outermost, so as 15 to be readily removed by stripping when said knives are narrowed by wear. The built-up spacers employed between angular knives have been heretofore cross-kerfed from one side only nearly their entire width, so as to 20 be bent to match said knives, the cross-kerfing of some of these fillers being from the right side and that of others from the left side. From the fact that the spacers are tapered in the direction of their depth, as well 25 as longitudinally, and their veneer plies are necessarily outermost the cutting of these spacers from a built-up block is expensive, because of waste in the matter of time and material. This type of spacer is also unsatisfactory in practice, because its veneer ply or 30 plies become unglued and fall away, to the detriment of the engine and stock therein under treatment.

Our invention has for its object to cheapen 35 production of wood spacers for the shells and cores or cones of paper-stock engines, as well as to avoid the objections to the built-up type of such spacers, and to provide spacers for the use specified that are universal in the 40 matter of bending to match angular knives and which may be turned end for end, according to the direction of the taper of the spaces they are to fill, said invention consisting in what is hereinafter particularly set 45 forth with reference to the accompanying drawings and subsequently claimed.

Figure 1 of the drawings represents a plan view of one form of wooden spacer in accordance with our invention partly broken away,

the same being designed for the shell of a 50 paper-stock engine; Fig. 2, a side elevation of the same; Figs. 3 and 4, vertical transverse sections of said spacer, respectively indicated by lines 3 3 and 4 4 in the first figure; Fig. 5, a perspective view of another 55 form of our improved spacer, the same being designed for a core or cone of a paper-stock engine; and Fig. 6, a transverse section of the latter form of spacer.

Referring by letter to the drawings, A in- 60 dicates a wood spacer for knives of the shell of a paper-stock engine, and A' a wood spacer for knives of the core or cone of such an engine, each of these spacers being a stick having one or more kerfs b its entire length 65 from both sides toward the center adjacent to its outer face, a thin central web of material being left between opposite kerfs, and in practice the material outermost from the kerfs is broken away in a strip when the ad- 70 jacent knives are worn close to what is then the outer face of the filler.

The spacer A is shown provided with a plurality of longitudinal kerfs b from each side thereof toward the center, whereby this 75 form of spacer is made to provide for the breaking away from the same of a plurality of outer strips in successive order from time to time as adjacent knives in a paper-stock engine become worn in practice. Spacer A 80 is also shown provided with transverse kerfs c from both sides toward the center intermediate of its ends, this kerfing being as deep as the longitudinal kerfs aforesaid and permitting the bending of said spacer either 85 right or left to match angular knives between which it may be interposed. The ends of the spacer are cut square, and said spacer may be turned end for end as the taper of the space it is to fill may require. 90

The spacers are tapered in the direction of their depth and length, as is customary with devices of this character, and said spacers being sawed from a single block the latter may be manipulated by the sawyer to save 95 time and material that is necessarily wasted in cutting spacers from built-up blocks. We also save the time and labor necessary to the

making of blocks from which to cut built-up spacers.

Having thus described our invention, what we claim as new, and desire to secure by Letters Patent, is—

1. A wood spacer for interposition between knives of the shell or core of a paper-stock engine and which consists of a stick provided with opposite longitudinal kerfs adjacent to its outer face.

2. A wood spacer for interposition between knives of the shell or core of a paper-stock engine and which consists of a stick provided with a plurality of longitudinal kerfs from each side thereof toward the center adjacent to its outer face.

3. A wood spacer for interposition between angular knives in a paper-stock engine and

which consists of a stick provided with opposite transverse kerfs intermediate of its ends. 20

4. A wood spacer for interposition between angular knives in a paper-stock engine and which consists of a stick having opposite longitudinal kerfs adjacent to its outer face and opposite transverse kerfs intermediate of its 25 ends.

In testimony that we claim the foregoing we have hereunto set our hands, at Appleton, in the county of Outagamie and State of Wisconsin, in the presence of two witnesses.

MARTIN P. VAN RYZIN.
HERMAN G. SAECKER.
